LUBRICATING APPARATUS

Frank S. Barks and Foster Holmes, St. Louis,
Mo., assignors to Lincoln Engineering Com-
pany, St. Louis, Mo., a corporation of Missouri

Application May 6, 1931. Serial No. 535,465

4 Claims. (Cl. 184—7)

This invention relates to lubricating apparatus and with regard to certain more specific features, to distributor means used in connection with such apparatus.

5 Among the several objects of the invention may be noted the provision of an improved coupler and indicating means for a distributing means described in the United States patent application of Frank S. Barks, filed November 14, 1930, Serial No. 495,596, for Lubricating apparatus; the provision of an indicator for distributing means of the class described which indicator is adapted to show the type and/or operation of said distributor; and, the provision of a coupler for 15 the distributing means of the class described which is adapted to provide an extendable connection between said distributor and pipes connected therewith. Other objects will be in part obvious and in part pointed out hereinafter.

20 The invention accordingly comprises the elements and combinations of elements, features of construction, and arrangements of parts which will be exemplified in the structures hereinafter described, and the scope of the application of 25 which will be indicated in the following claims.

In the accompanying drawing, in which are illustrated several of various possible embodiments of the invention,

Fig. 1 is a vertical, axial section taken on line 30 1—1 of Fig. 5, of a distributing means;

Fig. 2 is a detailed plan view of a modified form of an indicating means adapted to be applied to the distributing means;

Fig. 3 is a cross sectional view taken on line 35 3—3 of Fig. 2;

Fig. 4 is a cross sectional view taken on line 4—4 of Fig. 2;

Fig. 5 is a plan view showing distributors similar to those of Fig. 1 assembled; and,

40 Fig. 6 is a plan view similar to Fig. 5 but showing an alternative position of the distributors.

Similar reference characters indicate corresponding parts throughout the several views of the drawing.

45 Referring now more particularly to Fig. 1 there is shown a distributing lubricator such as is described in the said application of Frank S. Barks, hereinbefore mentioned; and, as shown in Figs. 5 and 6, the distributor is positioned between high pressure lubricating lines I and O which are ordinarily subjected to vibrations or like movements. The distributor comprises a body portion 1 having a cylinder 3 for slidably accommodating a packed main piston 5. The 55 main piston 5 is annular and slidably rides upon

and seals against a stem 7 of a piston valve. Said piston 5 comprises a metal center portion 6 with end portions 8 comprising packing. The valve comprises the stem 7 and two heads 9 and 11 at the left and right respectively.

The heads 9 and 11 of said piston valve reciprocate in cylinders 13 and 15 respectively, formed in bodies 17 and 19 which are threaded to the main body portion 1 and which have outlets 25 and 27 respectively communicating with cylinders 13 and 15. Packing 18 may be positioned between the portions 17 and 19 and the main body portion 1 to provide for angular adjustment of the portions 17 and 19 in order to properly rotate the outlets 25 and 27 to the directions they should assume.

Cylinders 13 and 15 are provided with inlets 29 and 32 in which are respectively threaded a nipple 69 and a sleeve 57 to be described hereinafter and which are respectively connected to the lines I and O. When the head 9 is in its right hand position, not shown, a by-pass 33 bypasses fluid from the inlet 29 and from the outer face of the head 9 to the left face of the main piston 5. Likewise the cylinder 15 is provided with a by-pass 35 which serves a purpose similar to that of the pass 33. It will be noted that when the head 9 is in its left hand position as shown in Fig. 1 the by-pass 33 is closed and the outlet 25 is in communication with the cylinder 13 and consequently with the bore 3 and at the same time, the head 11 allows communication between the inlet 32, the by-pass 35 and the cylinder or bore 3, at which time the outlet 27 is cut off from communication with the cylinder 15. When in its right hand position the head 9 cuts off the outlet 25 from the cylinder 13 but allows communication between the inlet 29, the by-pass 33 and with the bore 3, and at the same time the outlet 27 is in communication with the cylinder 15 and the by-pass 35 is shut off from the inlet 32.

The pressure in the lines I and O is controlled by an apparatus not to be described herein because it is not pertinent to the description of the invention, but it is noted that when high pressure exists in the line I a relatively low pressure exists in the line O and vice versa; and when a certain predetermined maximum pressure is reached in the line I the high pressure shifts from the line I to the line O and vice versa.

100 The operation of the distributor lubricator is as follows:

Assuming the line O to be now in its high pressure stage, the grease or other lubricating material contained therein is forced through the 110

line O to the inlet 32, into the cylinder 15, through the by-pass 35, into the bore 3 where its pressure is exerted against the piston 5. This pressure exerted against the piston 5 pushes it to the left thereby pushing any material which may be in the 5 left hand end of the bore 3 out of the outlet 25. When the piston 5 reaches the extreme left hand end of the bore 3, or when other unusual conditions come about which prevent flow of material 10 from the outlet 25 thus causing the pressure in the line O to reach the predetermined maximum pressure, the high pressure in the line O then shifts to the line I, and the line O is put under relatively low pressure.

15 With this change the pressure in the line I is conducted to the inlet 29, where it reacts against the head 9 to push the head 9 to the right, opening the by-pass 33, closing the outlet 25, opening the outlet 27 and closing the by-pass 35. Thus 20 the high pressure in the line I is communicated to the left hand end of the piston 5 which is moved to the right, forcing material in the right hand end of the bore 3 out through the outlet 27.

25 This operation is more fully explained in the hereinbefore mentioned application of Frank S. Barks, the present description being ample for the present purposes.

30 Inasmuch as the outlets 25 and 27 respectively communicate with bearings which are inherently likely to become stopped or closed to the passage of grease thereto, the piston 5 may be prevented from making complete strokes in the bore 3 because the hereinbefore mentioned predetermined maximum pressure in the lines I and O which 35 operates the valve stem 7 may build up before the piston 5 completes its stroke due to building up of a resistance in the outlets 25 or 27. Unless precautions are taken, foreign particles or obstructions in the lines 25 and 27 may operate to 40 prevent bearings from receiving the proper amount of lubrication due to the non-completed stroke of the piston 5. We have provided, however, a warning flag or indicating means 39 which is associated with the piston 5, and which reciprocates with the piston 5 in an opening 37 provided in the body portion 1. The indicator 39 45 comprises a stud 41 extending from the cylinder 6, of the piston 5, through an opening 37, through a slot 47 formed in a cover plate 43, which is held 50 on the body portion 1 by screws 45 and which is provided to keep dirt or other foreign material from entering the opening 37. Indicia 49 are provided to cooperate with the pointer 41 to indicate the position of the piston 5 in the bore 3.

55 Thus a signal is provided which at all times indicates the position of the piston 5 in its stroke. If for instance the outlet 25 has become stopped or closed, thereby preventing any substantial delivery of grease to its bearing, the flag 39 will 60 show that the piston 5 is not moving as far to the left as it should and steps may be taken to either increase the maximum pressure required in the line O before the pressure is transferred to the line I, or the bearing in communication with the line 25 may be cleaned.

65 In the form of the indicator 39 shown in Figs. 2, 3 and 4 the plate 43 is eliminated. The opening 37 is shallower because a portion 51 is cut out of the body portion 1 leaving sloping walls 70 53. The slot 37 is thus relatively shallow inasmuch as the cut 51 passes close to the bore 3. The stud 41 which is shorter than that of the Fig. 1 modification, is provided with a pointer 55. The pointer is formed with extensions 54 which 75 slope up from contact with the piston 5 and act

as a plow or the like to prevent dirt, which may accumulate in the slot 37, from being packed against the ends of the slot (Fig. 3). As in the Fig. 1 modification the indicia 49 cooperate with the pointer 55 to indicate the position of the 80 piston 5.

An advantage of such indicators 39 is that at a glance an operator can tell if the piston 5 is functioning properly and whether or not the outlets 25 and 27 are being properly supplied with 85 grease. Furthermore, in actual operation there may be a number of distributing lubricators between the lines I and O, each having a piston 5 of different length supplying respective bearings which require different amounts of grease. With the indicators 39 in position an operator can tell at a glance the size of the piston 5 which is in a particular lubricating distributor by the length of the stroke of the indicator. This may be of 90 particular advantage when changes are made in the lubricating system and/or when new bearings are installed.

95 Referring now to Fig. 1 again, the coupler 31, which is shown in position between the portion 19 and line O, comprises two sleeves 57 and 59 the latter telescoping into and movable in the former. The sleeve 59 enters the sleeve 57 through a guide 61 threaded on the sleeve 57. The guide 61 is adapted to keep packing 8' in place, which provides a seal between the sleeves 105 57 and 59. The sleeve 59 carries a collar 65 which reacts against a washer 63 to prevent the sleeve 59 from being removed from the sleeve 57. The sleeve 57 is threaded into the body portion 19 as shown in Fig. 1. The sleeve 59 is threaded into 110 an elbow 67 which in turn is threaded to a coupler in the line O by means of pipe threads.

115 The packing 8' may comprise any suitable packing, but the packing we prefer is described in detail in the United States patent application of Frank S. Barks, Serial No. 495,838, filed November 15, 1930, for Sealing means. This packing comprises alternate layers of canvas and thin rubber, and is substantially oil and grease resisting. Furthermore, it is adapted to radially expand, 120 uniformly throughout its length, when subjected to end pressure. An end pressure exerted by the fluid, in the sleeve 57, against the washer 63 thus seals the packing 8' around the sleeve 59.

125 The outlet 29 is connected with a coupler in the pipe I by means of a nipple 69 which is threaded to the portion 17, and to an elbow 71 which in turn is threaded into the coupler in the line I. The threads between the elbow 71 and nipple 69 and between the elbow and coupler in the line I are pipe threads and hence permit of a substantially amount of rotation between the threaded members without impairing the efficiency of the joint.

130 The provision of the coupler 31 and of such a joint at the outlet 29 allows considerable movement between the lines I and O connected by means of the distributor lubricators as shown. Thus if one or both of the lines I and O are connected to a piece of mechanism which is subject 140 to considerable vibration in one plane, the coupler 31 by means of the sliding connection of the sleeves 57 and 59, permits considerable displacement in the relative positioning of the lines I and O with or without changing the actual distance 145 between the two lines. Furthermore, the coupler 31 and the type of threading used at the outlet 29 between the nipple 69 and the elbow 71 allows the portions 17 and 19 to be angularly rotated to properly position the outlets 25 and 27. 150

The coupler 31 is also of distinct advantage to prevent stresses and strains which might otherwise occur in the distributor 2 due to non-synchronous vibration between the lines I and O. 5 Furthermore, the elbows 67 and 71 make the initial installation of the distributors 2 between the lines I and O much simpler. For instance in order to install a distributor 2 it is only necessary to thread the nipple 69 into the elbow 71, and the 10 sleeve 59 (separated from the sleeve 57) into the elbow 67 and then connect the sleeves 57 and 59 by means of the guide 61.

A further advantage of the coupler 31 is that in the installation of the distributors 2 between 15 the lines I and O accurate pipe work is not necessary inasmuch as the distance between the pipes I and O may be varied, because of the variable distance between the elbows 67 and 71 allowed by the movement between the sleeves 57 and 59. 20 Moreover, many of the vibratory shocks which would otherwise be transferred to the distributor 2 from the lines I and O are absorbed in the action between the sleeves 57 and 59 hence cheaper construction may be used in the distributors 2. 25 It is to be understood that the couplers 31 are also used to advantage at the outlets 25 and 27, especially if the bearings connected with the outlets are subject to movement.

In view of the above, it will be seen that the 30 several objects of the invention are achieved and other advantageous results attained.

As many changes could be made in carrying out the above constructions without departing from the scope of the invention, it is intended 35 that all matter contained in the above description or shown in the accompanying drawing shall be interpreted as illustrative and not in a limiting sense.

We claim:

40 1. Apparatus for distributing fluid from two sources under pressure, comprising a body portion having inlets and outlets, said inlets being connected to said sources, a plurality of bores in said body portion, an annular piston in at least one of said bores, valve heads in said other bores and a stem joining said heads and passing through said annular piston to form a valve exposed to said inlets, said piston and said valve being freely floating in their respective bores,

50

said body portion having a longitudinal slot formed therein, and an indicator mounted on said annular piston and extending through said slot whereby the operation of said piston is indicated by said indicator.

2. Apparatus for distributing fluid from two sources under pressure, comprising a body portion having inlets and outlets, said inlets being connected to said sources, a plurality of bores in said body portion, an annular piston in at least one of said bores, valve heads in said other bores and a stem joining said heads and passing through said annular piston to form a valve exposed to said inlets, said piston and said valve being freely floating in their respective bores, 80 said body portion having a slot formed therein, and an indicator mounted on said annular piston and extending through said slot whereby the operation of said piston is indicated by said indicator and means associated with said opening and indicator adapted to inhibit the interference of foreign material with the operation of said indicator.

3. Apparatus for distributing fluid from two sources under pressure, comprising a substantially rigid body portion having inlets and outlets, means for connecting said inlets with said sources, said means being adapted to allow rotational and angular movement of said body portion with respect to said sources, said means comprising an extensible coupler between at least one inlet and its source, and elbow fittings joining said inlets and said sources. 100

4. In combination with a substantially rigid distributor of the class described connected to inlet and outlet lines, a coupler effecting at least one of said connections, said coupler comprising telescoping sleeves slidably in but not normally removable from one another, packing between said sleeves being adapted to provide a 110 substantially fluid tight seal therebetween, said sleeves being respectively in communication with said distributor and one of said lines, an elbow joining one sleeve, with one of said lines and another elbow joining the device to said other 120 lines.
